COMMINUTOR

Augustus C. Durdin, Jr., Chicago, Ill.

Application March 7, 1940, Serial No. 322,639

9 Claims. (Cl. 210—152)

This invention relates to comminutors and particularly to comminutors of the rotary screen type which are employed for comminuting solids carried by liquids such as is the case in sewage. Comminutors intended to comminute solids carried by liquids normally comprise a screen through which the liquid passes. The solids are retained by the screen and they are subjected to comminution by devices of various kinds. In one well known form of comminutors a rotary screen is employed, the liquid passing from the exterior into the interior of the screen, from whence it flows to a suitable outlet channel. The rotary screen is normally provided with teeth which cause retained solids to move with the screen. These teeth cooperate with suitable stationary cutting mechanism to effect comminution of the solids.

A problem arises with comminutors of this type from the fact that solids carried by liquids for the most part either sink or float, since it is only occasionally that solid material has exactly the same specific gravity as the water which carries the solids.

One of the principal objects of the present invention is to provide an improved comminutor in which the liquid is caused to pass around a screen with a whirling or rotating movement relative to its direction of flow. The rotating movement or whirling of the stream causes all the solids therein, both the normally floating solids and the normally sunk solids, to perform orbits within the floating stream. Since the stream is draining through the screen, the solids are presented to the screen at various levels, ranging from water level down to the bottom of the screen. These solids are held against the screen by water pressure and are transferred to cutting mechanism, where they are comminuted. Consequently the cutting operation is distributed through the whole submerged depth of the screen and therefore no excessive wear occurs from normally floating solids at the water level and from normally sunk solids at the bottom of the screen.

A further object of the invention is to provide a comminutor in which the incoming stream of liquid and the movement of the stream combine to create a whirlpool which is adapted to return solids from which pieces have been cut back to the stream for further presentation to the screen.

The invention will more readily be understood from the following description, taken in conjunction with the accompanying drawing, in which:

Figure 1 is a perspective view, partly broken

away, showing a comminutor and comminutor chamber equipped with means for imparting a rotary or whirling motion to the stream passing around the comminutor screen;

5 Fig. 2 is a longitudinal sectional view of the device in Fig. 1, the section being taken on the line 2—2 of Fig. 1, and

Fig. 3 is a similar view showing my invention in a modified form.

10 Referring to the drawing, the reference numeral 10 indicates a concrete structure in which the comminutor is located. The incoming sewage enters by the conduit 11, from which it may be directed through a channel 12 to either one of 15 two comminutors, only one of which is illustrated. The channels 12 are provided with guideways 13 for the reception of slide plates to direct the flow through only one of the channels 12.

Each of the channels 12 leads into a comminutor chamber 14, the outlet of which is a U-shaped conduit 15 extending from the bottom of the chamber 14 to an egress conduit 16.

The comminutor comprises a casting 17 upon which is rotatably mounted the screen 18. The screen 18 carries teeth 19 which are adapted to engage solid materials and carry them into engagement with a stationary comb 20 which is mounted on the casting 17. In passing through the comb the teeth 19 tear small pieces out of the solid objects, which small pieces pass through the screen 18 into the egress channel 16. Eventually the complete solid object is comminuted into small pieces and passed into the egress stream.

35 The comminutor chamber 14 is substantially circular in plan and the screen 18 is located in eccentric relation therein so that the liquid entering through the channel 12 is presented with an initially wide path which gradually narrows 40 around the screen. The casting 17 comprises a vertical portion 21 which closes this path adjacent one side of the associated channel 12. The casting 17 also comprises a boss 22 upon which is mounted the motor 23 which drives the screen 45 18. The comminutor is maintained in position by means of nuts 24 with its annular base 25 around the entrance of the ejection conduit 15. The channel 12 enters the chamber 14 in substantially tangential relation thereto as is best seen in Figure 1.

Means are provided for imparting to the stream of liquid flowing around the screen, a whirling or rotary movement around the general axis of the stream. Thus, in Figs. 1 and 2 I have shown 50 a cradle structure 26 located in the bottom of

the channel 12. The structure 26 may suitably be formed of concrete and it may be integral with the concrete structure providing the channel 12 and the chamber 14. The cradle structure 26 provides an effective bottom for the channel 12 which is of substantially semi-cylindrical form.

Upon the interior surface of the cradle structure 26 are provided a plurality of vanes 27 which are arranged in sharply helical formation. These vanes are preferably in the form of helices of very steep pitch. At their forward ends, that is, the ends adjacent the inlet end of the channel 12, the vanes 27 are tapered down to substantial disappearance, as shown at 28, so that they present no sharp corners upon which rags or other debris might catch. The vanes 27 may suitably be formed integral with the cradle member 26, although they may be of different material if desired.

In the embodiment of the invention illustrated in Fig. 3, the channel 12 is closed off by two transverse partitions 30. Through these partitions extends a cylindrical structure 29, which is preferably located very close to the bottom of the channel 12. The cylindrical structure 29 may suitably be of metal and it is provided with helical vanes 31 which are substantially similar to the helical vanes 27 of the embodiment of the invention previously described. The helical blades 31 are tapered away at the inlet end of the cylindrical member 29 in the same manner as the vanes 27 are tapered at 28.

The two embodiments of the invention described above differ principally in that the second embodiment provides a cylindrical surface having vanes, whereas the first embodiment has a substantially semi-cylindrical surface provided with vanes. The vanes in both cases being arranged helically, impart to the liquid flowing around the comminutor screen 18 a whirling or rotary movement. This whirling or rotary movement causes a similar movement of solid materials in the stream; that is, solid materials which are normally submerged and solid materials which normally float are carried around by the whirling stream, so that they are presented to the screen 18 at various levels extending from the water level down to the bottom of the screen. When the solid materials are engaged by the screen 18, the water pressure tends to hold them in position and they are carried around so that they are disintegrated by the teeth 19 and the comb 20 in the manner described above.

The cutting operation is performed at the position of the comb 20, which is located within a recess or concavity 33 in the casting 17. This concavity is located alongside the point where the channel 12 enters the chamber 14. The flow of the stream entering from the channel 12 past the recess or concavity 33 and the movement of the screen, which is opposite to that of the stream, engenders a whirlpool in this recess or concavity. When the solid materials are disengaged from the screen as a result of the cutting operation at the comb 20, this whirlpool carries the disengaged solids outwardly into the incoming stream, which carries them around again for engagement with the screen 18 and the teeth 19 in the manner described above. The whirling nature of the incoming stream tends to maintain its course independent of the liquid in the whirlpool in the concavity 33, and the effect of the stream moving past the liquid in the whirlpool and the opposite movement of the screen ener-

gize and accentuate the whirlpool movement of the liquid in the concavity 33.

Although the invention has been disclosed in connection with the specific details of preferred embodiments thereof, it must be understood that such details are not intended to be limitative of the invention except in so far as set forth in the accompanying claims.

Having thus described my invention, what I claim as new and desire to secure by Letters Patent of the United States is:

1. In a comminutor comprising a rotary screen, means defining a path for a stream of liquid around the screen, an eduction passage within the screen, and means including vanes in said path and in a generally helical relation to the direction of said path for imparting a whirling or rotary movement to said stream.
2. In a comminutor comprising a rotary screen, means defining a path for a stream of liquid including a liquid supply conduit and wall means substantially enclosing the screen and in spaced relation thereto, and means including vanes located in said path, said vanes being in helical arrangement to the direction of flow for imparting a whirling or rotary movement to said stream.
3. In a comminutor comprising a rotary screen, means defining a path for a stream of liquid around the screen, an eduction passage within the screen and a conduit for supplying said stream of liquid to said path, and vanes in said conduit arranged in helical relation to the longitudinal direction of said conduit for imparting a whirling or rotary movement to said stream.
4. A comminutor comprising a rotary screen, a chamber receiving said screen in eccentric relation, a passageway entering said chamber in tangential relation, means extending between said screen and the wall of said chamber providing a substantial recess adjacent the point of entry of said passageway, cooperating cutting means on said screen and last said means, said passageway and the space between the chamber and screen defining a path for liquid, means including vane members arranged in said path and in a substantially helical relation thereto, whereby a rotary or whirling motion is imparted to the liquid passing around the screen in said chamber, and means for rotating said screen so as to carry solid materials into said recess where portions are severed therefrom, whereby the stream entering by the passageway and the movement of said screen are adapted to create a whirlpool in said recess which is adapted to return solid materials to said stream.
5. A comminutor comprising a rotary screen, a chamber receiving said screen in eccentric relation, a passageway entering said chamber in tangential relation, means extending between said screen and the wall of said chamber providing a substantial recess adjacent the point of entry of said passageway, cooperating cutting means on said screen and last said means, vane means in said passageway and arranged in a substantially helical relation thereto for imparting a rotary or whirling motion to liquid passing through said passageway and around the screen in said chamber, and means for rotating said screen so as to carry solid materials into said recess where portions are severed therefrom, whereby the stream entering by the passageway and the movement of said screen are adapted to create a whirlpool in said recess which is adapted to return solid materials to said stream.
6. A comminutor comprising a substantially

circular chamber, a screen eccentrically arranged in said chamber, a passageway entering said chamber in substantially tangential relation so as to supply a stream of liquid to a gradually converging path around said screen, stationary means and means on said screen in cooperating cutting relation, means for rotating said screen to cause said cutting means to operate on solid materials, a cradle member in said passageway and vane members on said cradle in a substantially helical relation to the longitudinal direction of said passageway whereby the entering stream is caused to rotate or whirl around the general axis of the stream.

7. A comminutor comprising a substantially circular chamber, a screen eccentrically arranged in said chamber, a passageway entering said chamber in substantially tangential relation so as to supply a stream of liquid to a gradually converging path around said screen, stationary means and means on said screen in cooperating cutting relation, means for rotating said screen to cause said cutting means to operate on solid materials, means in said passageway defining an enclosed conduit and vane members in said conduit and in a substantially helical relation to the longitudinal direction of said conduit whereby the entering stream is caused to rotate or whirl around the general axis of the stream.

8. A comminutor comprising a substantially circular chamber, a screen eccentrically arranged in said chamber, a passageway entering said chamber in substantially tangential relation so as to supply a stream of liquid to a gradually converging path around said screen, stationary means

and means on said screen in cooperating cutting relation, a cradle member in said passageway, vane members on said cradle and arranged in a substantially helical relation to the longitudinal direction of said cradle whereby the entering stream is caused to rotate or whirl around the general axis of the stream, and means extending between said screen and the wall of the chamber adjacent the said passageway defining a recess, and means for rotating said screen in a direction opposite to said stream to cause said cutting means to operate on solid materials, whereby the incoming stream and the rotation of said screen engender a whirlpool in said recess.

9. A comminutor comprising a substantially circular chamber, a screen eccentrically arranged in said chamber, a passageway entering said chamber in substantially tangential relation so as to supply a stream of liquid to a gradually converging path around said screen, stationary means and means on said screen in cooperating cutting relation, means in said passageway defining a closed conduit, vane members in said conduit and arranged in a substantially helical relation to the longitudinal direction of said conduit whereby the entering stream is caused to rotate or whirl around the general axis of the stream, and means extending between said screen and the wall of the chamber adjacent the said passageway defining a recess, and means for rotating said screen in a direction opposite to said stream to cause said cutting means to operate on solid materials, whereby the incoming stream and the rotation of said screen engender a whirlpool in said recess.
